BINDER

Filed July 2, 1928

UNITED STATES PATENT OFFICE

LOUIS A. PHILLIPS, OF TENAFLY, NEW JERSEY

BINDER

Application filed July 2, 1928. Serial No. 289,690.

The present invention relates to a hanger in the form of a semi-ring binder by means of which one or a plurality of loose leaves, such as the leaves of a calendar or cards bearing tabulations, charts and the like, may be hung upon a wall for ready reference, an object of the invention being to provide a suspension device of the character described on which loose leaves may be quickly bound and which is so constructed as to permit the leaves being conveniently turned over.

A further object of the invention is to form the device preferably from a single piece of wire with its leaf engaging or binding portions so relatively arranged and cooperating in such manner as to permit the leaves being readily bound and, when desired, removed from the binder without danger of being torn or otherwise mutilated.

20 And, a still further object of the invention is the provision, in a binder made in one piece from spring wire, of interlocking means for preventing removal of the bound leaves until manual disengagement of such locking means has been effected.

To these and other ends the invention consists of a suspension binder construction as will be fully set forth in the following description and particularly defined in the appended claims.

30 The accompanying drawings illustrating the invention are as follows:

Fig. 1 is a view in front elevation of the binder with leaves thereon;

35 Fig. 2 is a similar view in rear elevation; and

Fig. 3 is an end view of the device as shown in Figs. 1 and 2 with a portion of the leaves in section on line 3-3, Fig. 1.

40 In the drawings similar reference numerals refer to similar parts throughout the several views.

The binder comprises, preferably, a single piece of spring wire which at points 1 and 2, unequal distances from their respective ends, is bent laterally to form substantially semi-ring binding portions 3 and 4 projecting forwardly from a horizontal bar portion 5 formed at its center with an upwardly extending loop 6 adapted to engage over a

nail 7 or like support projecting from a side wall indicated at 8.

The free end of the curved or binding portion 3 is formed in the plane of such portion with an eye 9, and the wire at a point 10 in the similarly curved binding portion 4 is bent at right angles to provide a bottom or locking bar 11 lying both substantially parallel to and in the plane of the top bar 5, the free end of the bar portion 11 normally extending through the eye 9. To this end the bar 11 is made longer than the bar 5, and the loop 6 affords flexibility to the bar 5 which in turn gives the binder frame the necessary resiliency to spread the members 3 and 4 relatively apart to permit engagement and disengagement of the interlocking members, that is, the free end of the bar 11 and the eye 9.

Leaves or cards loosely bound and suspended by the binder are indicated at 12 and have perforations 13, 13 adjacent one edge of sufficient diameter to receive the eye 9, or other bar engaging formation of the wire on the free end of the curved portion 3.

These leaves or cards 12 are suspended on the binding portions 3 and 4 by first inserting the locking bar 11 through a perforation 13 of one or a plurality of leaves, swinging the binder substantially 90° about the point 10 as a center, inserting the eye 9 through the other perforation 13, and then spreading the binding portions 3 and 4 relatively apart to permit engagement of the end of the bar 11 through the eye 9, the resiliency of the frame returning the parts to normal positions. Thus, the leaves 12 are removably suspended on the semi-ring portions 3 and 4 and may be separately turned over by raising them to the dotted line position 14 indicated for one of the leaves.

From the foregoing it will be observed that I have provided a suspension binder of novel, simple, inexpensive and strong construction; that it comprises a single piece of spring wire bent to form a frame including semi-ring binding portions connected at the top by a bar portion made flexible by providing a loop therein, which also serves as means for hanging the binder on a nail or like support, and

at the bottom by a locking bar extending across the rear face of the bound leaves, the connection of this bar with one of the binding portions being separable, that is, the binder frame at one corner is breakable to permit placing the leaves on and removing them from the binder; and, that the flexibility of the top bar gives sufficient resiliency to the binder frame to permit engagement and disengagement of the co-operating locking parts which, in this instance, are the inflexible bottom bar 11 and the eye 9 through which the free end of such bar projects.

What I claim as my invention and desire to secure by Letters Patent is:

1. A binder of the character described comprising a single piece of spring wire bent laterally at points of unequal distance from its ends to form two semi-ring binding members 20 and a resilient cross bar connecting said members, a loop formed in the said cross bar, an eye formed on the free end of one binding member, and a locking bar extending integrally from the corresponding end of the other binding member, the free end of the said locking bar being slidable through said eye in interlocking engagement.

2. The combination with a leaf having perforations adjacent one edge, of a suspension binder therefor comprising a spring wire bent intermediate its ends to form a top bar and two laterally turned semi-ring binding members, an eye on the free end of one binding member, a locking bar extending from 35 the corresponding end of the other binding member, said latter bar being inserted through one of said perforations to suspend the leaf on one of the binding members, and said eye being inserted through another 40 perforation to suspend the leaf on the other binding member, and a loop formed in said cross bar as a means for suspending the binder on a projection and also as means giving flexibility to the binder to permit engagement and disengagement of the free end of the locking bar with said eye.

3. A suspension binder, of the character and for the purpose described, formed of spring wire and comprising a top bar, semi-ring binding portions bent laterally from said bar, one of said binding portions terminating in a bottom bar parallel to and in substantially the plane of the top bar, the other binding portion terminating in a part formed 55 to releasably engage in locking relation the free end of said bottom bar, and a loop formed in said top bar as a suspension means for the binder and to give flexibility to the binder, as and for the purpose set forth.

4. A binder of the character described comprising a single piece of spring wire bent laterally at points of unequal distance from its ends to form two semi-ring binding members and a cross-bar connecting said members, an eye formed on the free end of one

binding member, and a locking bar extending integrally from the corresponding end of the other binding member, the free end of the said locking bar being slidable through said eye in interlocking engagement, the said cross-bar being flexible to permit the necessary spring action for engagement and disengagement of the interlocking parts.

5. A binder of the character described comprising a single piece of spring wire bent laterally at points of unequal distance from its ends to form two semi-ring binding members, and a cross bar connecting said members, an eye formed on the free end of one binding member, and a locking bar extending from the corresponding end of the other binding member, the free end of the said locking bar being slidable through said eye in interlocking engagement, the said cross bar having a loop formed therein, the said loop providing means for suspending the binder on a projection, and also providing means whereby such bar is made flexible to permit the necessary spring action for engagement and disengagement of the interlocking parts.

6. A binder of the character described comprising a single piece of spring wire bent to form two parallel binding members, and two spaced bars connecting said members, one of the said bars being relatively flexible and the other relatively inflexible, the connection of the said inflexible bar with one of said binding members being separable.
